FLUORESCENT LAMPS CONSTRUCTED FOR USE IN CONVENTIONAL LIGHT FIXTURES

The general objects of this invention have been to provide a fluorescent form of lamp which could be substituted for the incandescent lamps used in various forms of light fixtures, such as table lamps, floor lamps and the like.

These and other desirable objects have been accomplished by constructing the fluorescent lamp tube in a compacted form to fit into an ordinary light fixture, having a screw contact form of base and carrying in the base both ballast and starter elements for the lamp tube.

Other objects and novel features of the invention are set forth and will appear in the course of the following specification.

The drawings accompanying and forming part of the specification illustrate present embodiments of the invention, but as will appear, structure may be modified and changed as regards such illustration, all within the true intent and scope of the invention as hereinafter defined and claimed.

FIG. 1 is a side elevation of one of the new lamps in completely assembled form.

FIG. 2 is a broken sectional and diagrammatic view, illustrating the three main parts of the lamp in separated relation.

FIGS. 3 and 4 are cross-sectional views of the lamp tube member and the ballast member on substantially the planes of lines 3-3 and 4-4 of FIG. 2.

FIG. 5 is a broken sectional view of a modified form of the lamp tube.

FIG. 6 is a broken cross-sectional view of a special form of ballast element.

FIG. 7 is a wiring diagram.

As shown in FIGS. 1 and 2, the lamp is made up of three main units; a fluorescent lamp tube member 10; a ballast unit 11 for the lamp and a terminal contact base 12, mechanically coupled together and electrically connected in compact form, such as to go into and be used in a conventional lighting fixture.

The means for mechanically and electrically connecting these three parts comprises four contact prongs, 13, 14, 15, 16 on the base of the tube section, which extend into and through the intermediate ballast unit, to the terminal contact member 12.

The first or fluorescent lamp unit is shown in FIG. 2 as made up of a suitable base 17, carrying an outer transparent cylindrical shell 18, the latter having a spaced inner shell 19, dependent from the upper closed end, extending short of the base and spaced laterally between outer and inner annular walls 20, 21, carried by the base.

These four spaced annular walls 18, 20, 19, 21, thus form a cylindrical zigzag staggered annular passage, closed at the opposite ends at 22 and 23 to provide closed chambers in side-by-side, but separated relation, on the base for the contained discharge electrodes 24 and 25.

The ballast unit 11 is shown in FIG. 2 as consisting of a winding 26 enclosed in a magnetic core 27 and having a contact 28 at one end, at the top in the illustration to receive the short contact prong 13, and a projecting terminal contact 29 at the opposite, lower end, riveted or otherwise connected with the flanged upper end of the screw shell contact 30.

The lower terminal contact member 12 is shown in FIG. 2 as 60 comprising the outer hollow screw shell contact 30 for engagement in an ordinary screw shell socket and a center contact 31 for engagement with the center contact of a screw socket and with the hollow of the screw shell contact providing space for containment of the starter 32 and condenser 33 for the lamp.

This lower unit of the three part combination has socket contacts 34, 35, 36 for the three blades 14, 15 and 16 of the lamp unit.

The ballast unit 11 has in the top of it, FIG. 4, openings 37, 38, 39, 40 for the four prongs of the lamp tube; the latter three of these openings extending entirely through the ballast unit for passage of the prongs 14, 15, 16 through the ballast unit into the corresponding contacts in the lower terminal contact unit.

FIG. 7 illustrates basic circuit connections, showing the screw shell contact 30, connected with one end of the ballast winding 26 and the latter connected at the opposite end with contact 28, engageable by prong 13 to connect that to one end of electrode 24 and the opposite end of the latter connected through blade 16 and contact 36 with one side of the starter 32, which has its opposite side connected by contact 34 and prong 14 with one end of companion electrode 25; the latter connected through blade 15 and contact 35 to the center contact 31.

The screw shell provides space also for the condenser 33, connected across the starter leads.

While the four blades of the lamp base; three of them extending through the ballast into the screw base of the lamp will hold the three parts together in properly assembled relation; additional means such as spring catches 41 may be provided for preventing accidental separation of the parts.

The screw shell contact 30 is indicated in FIGS. 1 and 2 as secured to the bottom of the ballast unit by a hook form lug 42 on the flange of the screw shell engaged with a stud 43 on the bottom of the ballast at one side and the fastening such as a rivet or screw 29, extending through the flange at the opposite side.

The lamp tube may be made up in various shapes to gain the necessary length in a compacted form. For example, it may simply be a tube doubled upon itself in U-form, and such a doubled tube may be twisted into spiral shape, or as a further example, the doubled tube may be redoubled on itself, as shown in FIG. 5, into a somewhat M formation 44.

The ballast is illustrated in FIG. 6.

In the form shown, the core is made up of annular soft iron laminations 45 of U-shaped cross section and successively of smaller size so as to fit in reverse order one within the other to form a compact annular core surrounding the coil.

The lamp tubes may be of approximately the same length as a conventional double ended fluorescent tube, but compacted to occupy substantially the same space as an ordinary incandescent lamp bulb so as to be useable in lamp lighting fixtures now in service.

The invention possesses the advantage of all parts of a fluorescent lamp being combined in a single structure which can be handled as such and used in the lamp sockets of light fixtures heretofore designed only for incandescent lamp bulbs.

I claim:

1. fluorescent lamp for conventional screw socket light fixtures, comprising:
  - a lamp base;
  - a fluorescent lamp tube on said base;
  - said lamp tube being extended longitudinally to form a fluorescent tube but compacted transversely to go into a conventional light fixture and having electrode chambers at opposite ends of the same in separated relation on said base;
  - electrodes in said chambers;
  - contact blades projecting from a said base;
  - an open center annular ballast unit adjoining said base;
  - a hollow screw shell terminal contact and center contact adjoining said ballast for cooperative engagement with the screw shell and center contacts of screw sockets in conventional light fixtures;
  - a ballast connecting contact on said ballast unit engageable by one of said prongs on said lamp base;
  - circuit completing contacts for said screw shell and center contacts engageable by other of said prongs;
  - said last mentioned prongs extending from said first mentioned lamp base through the open center of the ballast into engagement with said last mentioned circuit completing contacts;
  - a fluorescent starter element in said hollow screw shell contact;
  - circuit completing connections between said terminal contacts, ballast, starter and electrodes;
  - a screw shell terminal contact base on which said screw shell and center contacts are mounted; and

said fluorescent lamp base, ballast and terminal contact base being three separably connected units in end-to-end relation and of cross-sectional dimensions to go into the sockets of conventional lamp fixtures and held in longitudinal aligned relation by said prongs projecting from the fluorescent lamp base into and through the annular ballast into engagement with said circuit completing contacts on said terminal screw shell unit and whereby said ballast is held in releasable confined relation between said fluorescent tube unit and said terminal contact unit.

2. The invention according to claim 1 with said ballast including a core of annular rings of soft iron in U-shape cross section sized to nest one within another in oppositely faced relation.

5 3. The invention according to claim 1 with said lamp tube in the form of cylindrical shells of successively smaller diameters, in laterally spaced relation, with alternate ends of the same connected together in closed relation forming an annular zigzag passage.
